US00D964321S

(12) **United States Design Patent** (10) **Patent No.:** **US D964,321 S**
Bullimore et al. (45) **Date of Patent:** **** Sep. 20, 2022**

(54) **WAVEGUIDE**

- (71) Applicant: **Tymphany Acoustic Technology Limited**, Taipei (TW)
- (72) Inventors: **George Albert Bullimore**, Huizhou (CN); **Stuart Martin Hancock**, Huizhou (CN); **Gavin Jones**, Huizhou (CN)
- (73) Assignee: **Tymphany Acoustic Technology Limited**, Taipei (TW)
- (**) Term: **15 Years**
- (21) Appl. No.: **29/825,537**
- (22) Filed: **Feb. 2, 2022**

CLAIM

The ornamental design for a waveguide, as shown and described.

DESCRIPTION

FIG. 1 is a perspective view of a waveguide showing our new design;

FIG. 2 is a top plan view thereof;

(Continued)

FIG. 3 is a bottom plan view thereof; and,
FIG. 4 is a side plan view thereof.

1 Claim, 4 Drawing Sheets
